(74) Attorney, Agent, or Firm — Ohlandt, Greeley,
Ruggiero & Perle, LLP(57) **CLAIM**

The ornamental design for a flexible pouch, as shown and described.

DESCRIPTION

FIG. 1 is a front, top perspective view of a flexible pouch according to the present disclosure;

FIG. 2 is a front plan view of the flexible pouch of FIG. 1; FIG. 3 is a rear plan view of the flexible pouch of FIG. 1; FIG. 4 is a side view of the flexible pouch of FIG. 1, the opposite side being identical thereto;

FIG. 5 is a top view of the flexible pouch of FIG. 1; and, FIG. 6 is a bottom view of the flexible pouch of FIG. 1. The broken lines in the drawings illustrating environmental structure or boundaries that form no part of the claimed design.
